(57) CLAIM

The ornamental design for eyewear, as shown and described.

DESCRIPTION

FIG. 1 is front perspective view of eyewear, showing my new design;

FIG. 2 is a rear perspective view thereof;

FIG. 3 is a front view thereof;

FIG. 4 is a rear view thereof;

FIG. 5 is a top view thereof;

FIG. 6 is a bottom view;

FIG. 7 a right side view thereof (the left side view is symmetrical); and,

FIG. 8 is a perspective view of a modified embodiment of the design shown in FIGS. 1-7 with a lens opacity that does allow details of the eyewear to appear though it. The broken lines shown are for illustrative purposes only and form no part of the claimed design.
